UNITED STATES PATENT OFFICE.

CHARLES HALL, OF NEW YORK, N. Y.

MANUFACTURE OF BOLTS.

SPECIFICATION forming part of Letters Patent No. 252,661, dated January 24, 1882.

Application filed December 2, 1881. (No model.)

To all whom it may concern:

Be it known that I, CHARLES HALL, of the city and State of New York, have invented an Improvement in the Manufacture of Bolts, of 5 which the following is a specification.

Bolts have been manufactured by machines in which there is a plunger that upsets the iron rod and spreads the same into the cavity of the die. A machine of this character may 10 be seen in Letters Patent No. 88,783, granted April 13, 1869, and No. 44,623, granted October 11, 1864.

In bolt-machines the head can be made much more uniform in measurement where the solid 15 die is used than it can with a divided die, because particles of iron get in between the parts of the die and prevent them closing; but there is great difficulty in keeping the punch or plunger in the proper condition. Heretofore the effort has been to fit the plunger to the die as tightly as possible, both in solid and divided die machines, so that the head will 20 come out of the die in a finished condition; but in practice it is found that the duties performed by the punch and die are so severe that the steel at the end of the punch wears away 25 and cracks, and it is also impossible to feed in exactly the same quantity of iron for each head. Hence in some instances the die is not 30 filled and the head is imperfect, or else the metal is in excess, and a very thin film or fin is thrown out between the punch and the die, and this film breaks off and wedges in between the surfaces and prevents the proper movement 35 of the punch or plunger, scratches and strains the die, and renders the machine unreliable in use.

My invention is made for the purpose of insuring a perfectly full head, for discharging the 40 surplus material, for lessening wear upon the punch or plunger and the die, for preventing the lodgment of any particles of metal between the plunger and the die, and for increasing the length of time that the plunger and 45 die can be used without requiring to be ground or repaired.

In the drawings, Figure 1 represents a section of the holding-jaws, the die, and the punch. Fig. 2 is a perspective view, representing a bolt-head as it comes out of the machine, and Fig. 3 is a similar view of the bolt-head as finished off for sale.

The holding-jaws *a*, the die *b*, the cutter *c*, and the means for supporting and operating such devices are to be of any desired character— 55 such, for instance, as those shown in either of the foregoing Letters Patent. The die *b* is to be of the size of the exterior measurement of the bolt-head, and it is preferably of one piece of steel.

The punch or plunger *e* is to be operated by a cam or a crank, as in aforesaid Letters Patent; but instead of the same fitting the die accurately I make such plunger purposely smaller than the interior of the die and round 65 the edges slightly. The object of this is, first, to lessen the expense of making the plunger; second, to lessen the friction and wear between the plunger and the die; third, to leave a space between parts for the surplus metal to 70 be discharged in the form of a fin thrown out around the head of the bolt between the plunger and the die, such fin being of sufficient thickness to prevent it being broken when the plunger withdraws from the head. The result 75 of this mode of making the bolt-head is that the bar or rod can be fed in sufficiently to insure the required quantity of material for the head without the risk of damage to the dies and machine by too much iron in the head, and 80 there is no risk of the head not being formed up perfectly, for the metal will fill into all the angles of the die before there is any fin thrown out, because the surplus metal will not be thrown out as a fin until the whole of the head 85 has been exposed to a pressure equal to that required to make the iron pass into the narrow space between the plunger and the die. By this means a perfect head is insured and an escape for surplus metal provided. After the 90 bolts have been forged, the fin is to be cut off or removed by a suitable cutter or milling-tool. It is usually preferable to employ a cutter that will round the upper corners of the bolt slightly and shape the same as represented 95 in Fig. 3.

An emery-wheel or grinding tool may be used for smoothing the head or cutting off the fin.

The bolts may be heated to give a blue color to the metal at the end of the head.

The rounded edges of the plunger prevent any tendency of the plunger to cut or break the fin and the surface of the plunger remains smooth and flat, whereas in the ordinary plun-

ger the metal around the sharp edges is pressed inwardly and forms a slight ridge around the face of the plunger. Hence there will be a corresponding depression or groove around the top of the head.

5 I claim as my invention—

1. In a machine for forging bolt-heads, a die having a hole of the size and shape of the head, in combination with a plunger that is 10 designedly made sufficiently smaller than the die for a fin to be thrown out around the head for the discharge of the surplus metal from the die, substantially as set forth.

15 2. The method herein specified of making bolt-heads, consisting in feeding into the ma-

chine more of the rod or bar than is required for forming the head, pressing up the bolt-head in the die by means of a plunger, forming a fin around the bolt-head of the surplus metal, and removing such fin and finishing the top 20 of the bolt-head by cutting or grinding after the bolt is delivered from the machine, substantially as set forth.

Signed by me this 30th day of November, A. D. 1881.

CHAS. HALL.
